UNITED STATES PATENT OFFICE

2,488,594

PROTECTOR FOR THE BOTTOM EDGES
OF TROUSERS

Frank F. Hartlage, New Haven, Conn.

Application August 23, 1947, Serial No. 770,217

1 Claim. (Cl. 2—232)

1

This invention relates to an improvement in protectors for the bottom edges of trousers and while particularly adapted for trousers with cuffs, is equally applicable to trousers without cuffs.

The object of the invention is to provide protectors which may be readily stamped out of sheet metal and easily affixed in position, and the invention consists in the construction as herein-after described and particularly recited in the claim.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a fragmentary perspective view of the rear bottom portion of a trousers-cuff, showing two protectors attached thereto;

Fig. 2 is a fragmentary inner face view of the same with the trousers-cuff positioned to place the protectors on a level plane, but on a larger scale;

Fig. 3 is a sectional view on the line 3—3 of Fig. 2;

Fig. 4 is a sectional view on the line 4—4 of Fig. 2;

Fig. 5 is a perspective view of one of the guard-plates, detached; and

Fig. 6 is a perspective view of one of the foundation-plates, detached.

In carrying out my invention, I employ a guard-plate 10 having a rounded lower edge 11 and formed with two pointed prongs 12 and 13. Preferably, these prongs extend laterally from said guard-plate, with their lower edges normal to said guard-plate.

With the guard-plate 10 I use a foundation-plate 15 formed with slots 16 and 17 which align with the prongs 12 and 13. If the trousers-cuffs are creased, a protector should be placed on each side of the crease.

The guard-plates 10 are positioned so that the rounded edges 11 extend under the lower edge 18 of the cuff, and the prongs are pressed through the fabric and the foundation-plates set over the prongs which are turned down onto the foundation-plates which are covered by the turned-up

15 cuff-portion 19. The foundation-plates prevent the guard-plates from slipping when applied and also serve to provide a firm relatively-large area to effectively prevent the prongs from tearing or 20 pulling through the fabric.

By using two protectors, the trousers can be creased and re-creased without removing the protectors.

It is obvious that if the trousers are not to be 10 pressed, one protector will be sufficient.

It is also obvious that the protectors may be used on trousers without cuffs by placing the foundation-plates inside the hem.

The invention may be carried out in other specific ways than those herein set forth without departing from the spirit and essential characteristics of the invention, and the present embodiments are, therefore, to be considered in all respects as illustrative and not restrictive, and all 20 changes coming within the meaning and equivalency range of the appended claim are intended to be embraced therein.

I claim:

25 A protector for the bottom edges of trousers comprising a flat guard-plate having a rounded lower edge engageable with the lower edge of the trousers cuff and formed with inwardly-projecting pointed prongs, each of the said prongs extending laterally from the said guard-plate with 30 its lower edge normal to said guard-plate, said guard-plate adapted to be placed against the inner face of the trousers-cuff with the prongs extending outwardly, and a foundation-plate inside 35 of said cuff and formed with slots adapted and positioned to allow said prongs to pass through said slots and be turned down upon the said foundation-plate.

FRANK F. HARTLAGE.
